(57) **CLAIM**

The ornamental design for an outdoor mechanical timer, as shown and described.

DESCRIPTION

FIG. 1 is a perspective view of an outdoor mechanical timer showing the claimed design;

FIG. 2 is a top plan view thereof;

FIG. 3 is a bottom plan view thereof;

FIG. 4 is a first side elevational view thereof;

FIG. 5 is a second side elevational view thereof; and,

FIG. 6 is a front elevational view thereof.

The broken lines in the drawings depict environmental subject matter that forms no part of the claimed design.
